UNITED STATES PATENT OFFICE

ARNOLD OVERHOLT, OF MEDINA, OHIO

PORTABLE UNLOADING DEVICE

Application filed April 17, 1929. Serial No. 355,849.

This invention relates to a car unloading device, the general object of the invention being to provide a conveyor which is adapted to be placed under a track on which the car to be unloaded stands, whereby when the doors of the hopper car are opened, the material from the car will fall into the conveyor and be conveyed to a point to one side of the track, preferably into a portable elevator 10 which will raise the material and deposit it into a truck or other receiver.

Another object of the invention is to provide doors for controlling the flow of material into the conveyor, with means for operating the doors from one end of the device.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a sectional view through a track with a car thereon and the device arranged under the track and car and delivering the material into an elevator.

Figure 2 is a top plan view of the device.

Figure 3 is a section on line 3—3 of Figure 2.

Figure 4 is a section on line 4—4 of Figure 5.

Figure 5 is a section on line 5—5 of Figure 2.

In these views, the numeral 1 indicates a conveyor casing adapted to be placed under a track A on which the car B, to be unloaded, stands. The open top of the casing is so arranged as to receive the material falling from the car when the doors of the car are opened. One end of the casing is closed and its other end is open and this open end is placed over a part of a portable elevator C or the like. The endless belt 2 passes over the two end rollers 3, located at the ends of the casing, and over the intermediate rollers

4. The end rollers are fastened to their shafts 5 and the intermediate rollers are each of spool shape with the ends separate from the central or cylindrical part and all three parts loosely arranged on the shaft 6. The ends 55 rollers are preferably of the shape shown. The end roller, adjacent the closed end of the casing, is provided with sliding bearings 7 which are adjustable in their guideways by the bolts 8. This arrangement provides 60 means for tightening the belt. The other end roller is provided with a pulley 9 so that it can be belted to a motor, such as the motor 10 on the elevator.

Inclined shields 11 are placed on the upper side edges of the casing, the lower edges of the shields being of channel shape, as shown at 12, to receive the edges of the belt and thus protect the edges of the belt from damage by the material handled by the device. A shield 13 extends across the end of the device, adjacent its closed end.

Cross pieces 14 extend across the top of the casing and gates 15 are slidably supported by said pieces. These gates have channel 75 irons 16 on their lower faces for receiving rollers 17 on the long arms of bell cranks 18 which are pivoted to the side parts of the casing, at the top thereof. A rod 19 is connected to the short arms of the bell cranks 80 on each side of the casing so that when these rods are moved in one direction, the bell cranks will cause the gates to move toward each other, and when the rods are moved in an opposite direction, the bell cranks cause 85 the gates to move away from each other. Thus the gates can be adjusted to regulate the amount of material entering the conveyor device. The ends of the gates slide in the guideways 20 at the ends of the casing.

From the foregoing it will be seen that I have provided a device which can be easily and quickly placed under a car and which will remove material dropping through the open door of the car and convey said material to a portable elevator or the like. Thus a car can be quickly unloaded with but little effort on the part of the men carrying out the unloading operation, and pits and overhead tracks are eliminated.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

- 10 1. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt and adjustable gates in the top of the casing for controlling the flow of material onto the belt.
- 15 2. An unloading device of the class described, comprising a casing having its top and one end open, a roller journaled in each end of the casing, intermediate rollers in the casing, shafts for the same and on which the rollers are loosely mounted, each intermediate roller being of spool shape with its ends separate from the center, an endless belt passing over the rollers, shields at the sides of the casing and having channel shaped lower edges for receiving the edges of the belt and adjustable gates in the top of the casing for controlling the flow of material onto the belt.
- 20 3. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel-shaped lower edges for receiving the edges of the belt, adjustable gates in the top of the casing for controlling the flow of material onto the belt, each gate extending longitudinally of the casing and having channels in its under face, bell cranks on each side of the
- 25 4. An unloading device of the class described, comprising a casing having its top and one end open, a roller journaled in each end of the casing, intermediate rollers in the casing, shafts for the same and on which the rollers are loosely mounted, each intermediate roller being of spool shape with its ends separate from the center, an endless belt passing over the rollers, shields at the sides of the casing and having channel shaped lower edges for receiving the edges of the belt and adjustable gates in the top of the casing for controlling the flow of material onto the belt.
- 30 5. An unloading device of the class described, comprising a casing having its top and one end open, a roller journaled in each end of the casing, intermediate rollers in the casing, shafts for the same and on which the rollers are loosely mounted, each intermediate roller being of spool shape with its ends separate from the center, an endless belt passing over the rollers, shields at the sides of the casing and having channel shaped lower edges for receiving the edges of the belt and adjustable gates in the top of the casing for controlling the flow of material onto the belt.
- 35 6. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel-shaped lower edges for receiving the edges of the belt, adjustable gates in the top of the casing for controlling the flow of material onto the belt, each gate extending longitudinally of the casing and having channels in its under face, bell cranks on each side of the
- 40 7. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the
- 45 8. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the
- 50 9. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the
- 55 10. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the
- 60 11. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the
- 65 12. An unloading device of the class described, comprising a casing having its top and one end open, a roller journaled in each end of the casing, intermediate rollers in the casing, shafts for the same and on which the rollers are loosely mounted, an endless belt passing over the rollers, shields at the sides of the casing and having channel shaped lower edges for receiving the edges of the belt, adjustable gates in the top of the casing for controlling the flow of material onto the belt, each gate extending longitudinally of the casing and having channels in its under face, bell cranks on each side of the

In testimony whereof I affix my signature.
ARNOLD OVERHOLT.
